UNITED STATES PATENT OFFICE.

CHARLES A. BREWER, OF CHICAGO, ILLINOIS, ASSIGNOR TO CHARLES A. BREWER & SONS, OF CHICAGO, ILLINOIS, A PARTNERSHIP CONSISTING OF CHARLES A. BREWER, NELSON C. BREWER, KENNETH E. BREWER, AND EVERETT R. BREWER.

SALES-BOARD.

1,309,349.

Specification of Letters Patent. Patented July 8, 1919.

Application filed March 15, 1919. Serial No. 282,835.

To all whom it may concern:

Be it known that I, CHARLES A. BREWER, a citizen of the United States, residing at Chicago, in the county of Cook and State of Illinois, have invented certain new and useful Improvements in Sales-Boards, of which the following is a specification.

This invention relates to what are commonly known as sales boards, of the character typically disclosed in Letters Patent to Brewer, and Scannell No. 780,086, dated January 17, 1905. These devices consist substantially of a board containing a number of transverse holes in which are loaded slips of paper containing various indicia, the ends of the holes being sealed by paper sheets, and the slips being ejected by a punch. These devices may be variously used, either for the vending and advertising purposes set forth in the aforesaid Letters Patent, or as a game board for educational and amusement purposes; as, for instance, the paper slips may contain the letters of the alphabet printed thereon, and the object of the game may be to see which of the players can first punch out enough letters to build a word, or the slip may contain numerals printed thereon and the object of the game may be to see who can punch out the highest aggregate or sum in a given number of punches.

One annoyance that has developed in connection with the use of these devices is the liability of losing the punch or key, which a user is very liable to thoughtlessly slip into his pocket and carry away. Still another disadvantage connected with the packing and shipping of these devices in bulk resides in the fact that space must be provided for the punches or keys, thereby necessitating some waste space over what is required for the packaging of a considerable number of the plain rectangular boards. Furthermore, punches when packed in a package with boards are frequently lost, as the punch package is small, and the person unpacking the boards does not find it, leaving it with the waste.

With a view to obviating the above mentioned objections and defects I have devised the improvement forming the subject matter of the present invention, which I will now proceed to describe.

The invention is illustrated as to structure and mode of use in the accompanying drawing, in which—

Figure 1 is a rear elevation of the sales board, broken out between its upper and lower ends, and showing the punch or key disposed in the pocket provided therefor in the upper edge of the board; and

Fig. 2 is a vertical section on the line 2—2 of Fig. 1.

Referring to the drawing, 5 designates as an entirety the board itself which, in the instance shown, is made up of a plurality of 6 heavy cardboard sheets 6 pasted together to produce a laminated structure and containing the transverse perforations or apertures 7. Both ends of these apertures are sealed by thin sheets 8 of easily perforated paper, and over the sheets 8 are pasted thin perforated cardboard sheets 9 having holes registering with the main holes 7 and serving as guides for the application of the punch or key 10; the thin sealing sheets 8 being preferably of a different, contrasting color from the outer guide sheets 9, so as to readily indicate the proper points of application of the key. Within the holes 7 are loaded the folded or curled paper slips 11 containing the printed indicia or symbols, the character of which depends upon the use and purpose of the device.

In the upper edge of the board I form a recess or pocket 12 of the proper size and shape to tightly fit and contain the punch 10. In the particular structure of board here shown this may very easily be done by cutting a relatively deep notch 12' in one of the cardboard members 6 of the structure, and cutting a somewhat shallower and registering notch 12" in the outer sheet 9. The key is readily inserted, point foremost, in this pocket in the manner clearly indicated in Fig. 1, the sides of the key fitting the sides of the pocket with sufficient friction to prevent the key from falling out even when the board is inverted, and the outer notch 12" facilitating its extraction by the thumb and finger of the user. To prevent the liability of the key becoming lost or mislaid or being accidentally carried away, I preferably attach the key to the board by a cord 13 of sufficient length to permit application

of the key to any of the holes of the sales board.

It will readily be seen from the foregoing how my present improvement accomplishes the stated objects of the invention. By permanently attaching the key to the board by a cord or string, I prevent the loss of the key, and by providing the pocket for the reception of the key I am enabled to dispose of the latter for shipment with the board without requiring any more packing and shipping space than is required for the board alone, as well as avoiding loss of the key through oversight in unpacking. There is a distinct advantage in a pocket opening through the edge of the board and snugly fitting the key, since no closure for the pocket is required, and such a pocket forms a permanent place to keep the key when not in use. The blank space at the head of the board, both front and rear, is frequently used for advertising purposes, and it will be seen that my improvement does not appreciably interfere with the use of this space for such purposes.

Although I have shown and described a laminated board, it will be understood that this specific structure of board is not of the essence of the invention, since a one piece board of wood or other material may be used, with the key-receiving pocket suitably mortised therein.

I claim:

1. A sales board of the character described, having formed in one edge thereof an inwardly extending pocket lying wholly within the surface boundaries of said board and

shaped to receive and snugly fit a punch inserted therein.

2. A sales board of the character described, having formed therein a pocket to receive and hold a punch, said pocket having an end opening in one edge of the board and a shallow side opening in one side of the board continuous with said end opening and of less depth than the depth of the pocket.

3. A sales board of the character described, having formed therein a pocket to receive and hold a punch, said pocket having an end opening in the upper edge of the board and a shallow side opening in the rear side of the board continuous with said end opening and of less depth than the depth of said pocket.

4. The combination with a sales board having formed in one edge thereof an inwardly extending pocket having side walls lying between the front and rear sides of the board, of a punch adapted to snugly fit and lie wholly within said pocket, and a cord by which said punch is permanently attached to said board.

5. The combination with a sales board having formed therein a pocket to receive and hold a punch, said pocket having side walls lying between the front and rear sides of the board, an end opening in the upper edge of said board, and a shallow side opening in the rear side of said board continuous with said end opening, of a punch snugly fitting and wholly contained within said pocket, and a cord by which said punch is permanently attached to said board.

CHARLES A. BREWER.
